(57) **CLAIM**

The ornamental design for a nozzle assembly, as shown and described.

DESCRIPTION

FIG. 1 is a first perspective view of the nozzle assembly apparatus of the invention;

FIG. 2 is a top view of a lever used in the nozzle assembly apparatus illustrated in FIG. 1;

FIG. 3 is a side view of the lever illustrated in FIG. 2;

FIG. 4 is a front view of the lever illustrated in FIG. 2;

FIG. 5 is a rear view of the lever illustrated in FIG. 2;

FIG. 6 is a bottom view of the lever illustrated in FIG. 2;

FIG. 7 is a second perspective view of the nozzle assembly apparatus of the invention shown in an alternate position;

FIG. 8 is a perspective view of the lever illustrated in FIG. 2, shown attached to an attachment ring used in the invention;

FIG. 9 is a top view of the lever and attachment ring illustrated in FIG. 8;

FIG. 10 is a side view of the lever and attachment ring illustrated in FIG. 8;

FIG. 11 is a front view of the lever and attachment ring illustrated in FIG. 8;

FIG. 12 is a rear view of the lever and attachment ring illustrated in FIG. 8;

FIG. 13 is a perspective view of the underside of the lever and attachment ring illustrated in FIG. 8;

FIG. 14 is a perspective view of a nozzle assembly used in the invention;

FIG. 15 is a top view of the nozzle assembly illustrated in FIG. 14;

FIG. 16 is a first side view of the nozzle assembly illustrated in FIG. 14;

FIG. 17 is a second side view of the nozzle assembly illustrated in FIG. 14; and,

FIG. 18 is a bottom view of the nozzle assembly illustrated in FIG. 14.

The broken lines in the Figures are for illustrative purposes only and form no part of the claimed design.
